UNITED STATES PATENT OFFICE

2,575,937

FLUID PRESSURE CONTROLLED ACTUATING DEVICE

Arthur J. Bent, Pittsburgh, Pa., assignor to Westinghouse Air Brake Company, a corporation of Pennsylvania

Application November 26, 1949, Serial No. 129,651

11 Claims. (Cl. 121—41)

1
This invention relates to a booster power device or fluid motor and more particularly to the type for controlling operation of devices such as the rudder or the ailerons of an airplane.

One object of the invention is to provide an improved fluid motor of the above type.

Another object of the invention is the provision of a relatively long stroke fluid motor wherein the quantity of fluid under pressure to be exhausted from one side and supplied to the opposite side of a reciprocating piston of the motor for effecting a short stroke of said piston, is materially less than in the conventional type of motor.

Still another object of the invention is the provision of a fluid motor such as above described, in which, for a short stroke, the motor piston is more quickly operative in response to a change in pressure than the piston of the usual type of fluid motor.

Other objects and advantages will be apparent from the following more detailed description of the invention.

In the accompanying drawings; Fig. 1 is a plan view of a rudder booster system for an airplane constructed in accordance with one embodiment of the invention; Figs. 2 and 3, taken together, with the left hand end of Fig. 3 abutting the right hand end of Fig. 2, is a longitudinal sectional view of a fluid motor shown in elevation in Fig. 1, the major portion of Fig. 3 being drawn to a slightly larger scale than Fig. 2 to more clearly show certain details; Fig. 4 is a sectional view taken on the line 4—4 of Fig. 2; and Fig. 5 is a sectional view showing at an enlarged scale certain details of the power cylinder shown in Fig. 2.

Description

As shown in Fig. 1 of the drawing, the reference numeral 1 designates the improved double acting fluid motor which includes a valve mechanism, carried in the interior of a piston rod 2 for controlling operation of said motor. The fluid motor 1 is adapted to be pivoted at one end by a pin 3 to any fixed member 4 such as a portion of the frame of an airplane. Extending from the opposite end of the fluid motor is the piston rod 2 which is connected to a rudder operating lever 5 pivoted on a rudder post 6 carried by the above mentioned frame. For providing manual control of the rudder, a pulley 7 having spaced, parallel and integrally connected arms 8, formed integral therewith and disposed one at either side of lever 5, is also pivoted on the rudder post 6. As shown in Fig. 3 of the drawings, the arms 8 are connected to the above mentioned valve mech-

2
anism carried by the piston rod 2 by means of a pin 9 extending through each of said arms and one arm of a bifurcated yoke 10, forming a part of said mechanism, for operating said mechanism in a manner later to be described. Passing around the pulley 7 is a cable 11 having the ends thereof connected to a foot operating lever 12 on opposite sides of a fulcrum pin 13 for said lever, said pin also being carried by the frame of the airplane. Fastened to the ends of the foot operating lever 12 are pedals 14 and 15 to provide means whereby a pilot may rock lever 12 in a clockwise or a counterclockwise direction about pin 13 by pushing on one or the other of the pedals.

The booster power cylinder 1 comprises a cylinder body 16 having a through bore 17 containing a main power piston 18 adapted for reciprocation within said bore. One end of the piston rod 2 is secured by screw-threaded engagement to the main power piston 18. The piston rod 2 is provided with means later to be described, for conveying fluid under pressure to and from one or the other of the faces of the piston 18. Slidably mounted in the bore 17 are two false pistons 19 and 20 one being disposed on each side of the main piston 18 and the false piston 20 being provided with a bore 21 through which projects the piston rod 2. The three pistons 18, 19 and 20 thus disposed in bore 17 form therein four pressure chambers 22, 23, 24 and 25, the chambers 22 and 23 being on the left and right hand sides, respectively, of the false piston 19, and chambers 24 and 25 being on the left and right hand sides, respectively, of the false piston 20 and the chambers 23 and 24 being at opposite sides of the piston 18. Each of the pistons 18, 19 and 20 is provided with a gasket ring 26 the peripheral surface of which is in sealing and sliding contact with the wall of bore 17 to prevent leakage of fluid under pressure from the chamber located at one side of the respective piston to the chamber located at the opposite side thereof.

Secured at one end to the false piston 19 by screw-threaded means is a stem 27 extending through the chamber 22 to the exterior of the cylinder body 16 and having formed at the opposite end a collar 28 for engagement with a stop member 29 screw-threaded into a pressure head 30 secured to the left hand end of the cylinder body 16 by any suitable means (not shown).

Disposed between the pressure head 30 and the left hand face of false piston 19 is a coiled spring 31 for biasing said piston in the direction of the right hand to a position in which the collar 28

engages the stop 29 as shown in Fig. 2 of the drawing.

A passageway 32 formed in the stem 27 is adapted to register with a passageway 33 formed in the false piston 19, said passageways constituting a fluid pressure communication between a valve mechanism 34 hereinafter described, and atmosphere.

Secured at one end to the false piston 20 by means of screw-thread engagement is one end of a stem 35 extending through the chamber 25 to the exterior of the cylinder body 16 and having formed at the opposite end a collar 36 for engagement with a stop member 37 screw-threaded into a pressure head 38 secured to the right hand end of the cylinder body 16 by any suitable means (not shown).

Disposed between the pressure head 38 and the right hand face of false piston 20 is a coiled spring 39 for biasing said piston in the direction of the left hand to a position in which the collar 36 engages the stop 37 as shown in Fig. 2 of the drawings.

The stem 35 is provided with an axial bore 40 through which projects the piston rod 2 in sliding contact with said stem. A passageway 41 formed in the stem 35 in one side of the bore 40, as best seen in Fig. 4, is adapted to register with a passageway 42 formed in the false piston 20 said passageways constituting a fluid pressure communication between a valve mechanism 43, identical with the valve mechanism 34, and atmosphere.

The valve mechanisms 34 and 43 are identical but oppositely arranged and are carried by the respective false pistons 19 and 20. Referring to Fig. 5 of the drawings, each of the false pistons is provided with a chamber 44 in which is situated a valve seat in the form of a collar 45 having a stem 46 slidably disposed in a bore 47 in the respective false piston, said stem extending into the respective chamber 23 or 24. The stem 46 is provided with a central passageway 48 extending through the seat on the collar 45 at one end of said stem and connected adjacent the opposite end to the peripheral surface of the stem through a series of ports 49. The peripheral surface of the stem 46 is in sealing and sliding contact with a gasket ring 50 clamped between the respective false piston 19 or 20 and a cap nut 51 screw-threaded into that face of the false piston adjacent the chamber 23 or 24. Disposed between the cap nut 51 and a collar 52, having screw-threaded engagement with the end of the stem 46 opposite the collar 45, is a spring 53 for normally biasing the collar 45 into engagement with a stop 54 on the respective false piston at that end of the bore 47 adjacent the chamber 44.

Disposed within the chamber 44 is a flat disc type supply valve 55 for cooperating with the seat 45 to control communication between the respective chamber 23 or 24 and the chamber 44. The supply valve 55 has spaced circumferentially on the outside of the seating portion thereof a series of ports 56 establishing communication between the opposite sides of said valve. A spring 57 is disposed in chamber 44 between supply valve 55 and a wall 58 of an exhaust valve cage 59 for urging said valve against its seat on collar 45.

The cage 59 is contained in chamber 22 or 25, as the case may be, and screw-threaded into the respective false piston. The valve cage 59 is provided on the side of the wall 58 opposite that

engaged by the spring 57 with a chamber 60. Extending for a chosen distance into the chamber 60 is an annular valve seat 61 through which extends a bore 62 said bore being coaxial with the bore 47 and opening into the chambers 44 and 60. Extending into the chamber 60 and concentric with the annular valve seat 61 is a shoulder 63 disposed from the wall 58 the same distance as the end of the annular valve seat 61.

Disposed within the chamber 60 is a flat disc type exhaust valve 64 for cooperating centrally with the seat 61 to control communication between the respective chambers 44 and 60. The exhaust valve 64 has a plurality of spaced ports 65 for establishing a fluid pressure communication between opposite sides of said valve whenever said valve is moved out of seating engagement with the shoulder 63, and which communication is closed when said valve is in contact with said shoulder. The exhaust valve 64 is provided with a fluted stem 66 projecting through the bore 62 into the chamber 44 and having its end disposed a chosen distance from the supply valve 55, when both valves are seated, to permit movement of said supply valve against the force of the spring 57 from its seat 45 said chosen distance without effecting the unseating of the exhaust valve 64.

In each of the false pistons 19 and 20 is a passageway 67 having a capacity substantially less than the capacity of passageways 71 and 73 and constituting a fluid pressure communication between the chamber 44 at the spring side of the supply valve 55 and the respective chamber 22 or 25.

The outer end of the chamber 60 is closed by a cap 68 having screw-threaded engagement with the exhaust valve cage 59, and supported by said cap and bearing against the valve 64 is a spring 69 for urging said valve to its seated position. A port 70 in the cap 68 connects the chamber 60 at the spring side of the exhaust valve 64 to the respective chamber 22 or 25.

The piston rod 2 is provided with a central passageway 71 of greater flow capacity than the passageway 67 in false piston 19 for a reason which hereinafter will be made apparent. The passageway 71 registers at its end adjacent the main piston 18 with a central passageway 72 in the main piston 18, said passageways providing a communication through which fluid under pressure may be supplied to and released from the chamber 23. Concentric with the passageway 71 in the piston rod 2 is a second passageway 73, also of greater flow capacity than the passageway 67 in false piston 20, for a reason which hereinafter will be made apparent, one end of said passageway 73 terminating at the peripheral surface of said piston rod adjacent the right hand face of the main piston 18, as shown in Fig. 2 of the drawing. The passageway 73 provides a communication through which fluid under pressure may be supplied to and released from the chamber 24.

The end of piston rod 2 opposite the piston 18 is provided with a counterbore 74 (see Fig. 3) in which is disposed a valve mechanism 75 for controlling the supply and release of fluid under pressure to and from the passageways 71 and 73.

The valve mechanism 75 comprises a sleeve 76 slidably disposed in the counterbore 74. The end of the sleeve 76 opposite the passageways 71 and 73 is tapped to receive a cap 77 having a stem 78 to which the yoke 10 is secured as by a nut 79. The yoke 10 is bifurcated and its ends

are connected respectively to arms 8 by means of the pins 9, as hereinbefore mentioned, to effect movement of the sleeve 76 within the bore 74 in response to rocking of said arms about the rudder post 6.

The sleeve 76 is provided with an off-center bore 80 extending from near the left hand end of the sleeve to one end of a coaxially arranged and larger bore 81 also in said sleeve and which extends to the opposite end of the sleeve. Slidably mounted in the bore 80 is a plunger 82 one end of which extends beyond the end of the sleeve 76 and is screw-threadedly connected to the piston rod 2. The plunger 82 is provided with a counterbore 83 open at its outer end to the passage 73 in the piston rod 2 and a plurality of ports 84 adjacent its right hand end connecting said counterbore to the peripheral surface of said plunger and thence to a passageway 85 extending through the sleeve 76 and opening into the bore 81. Secured by screw-threads to the right hand end of the plunger 82 and slidably mounted within the bore 80 is an exhaust valve seat member 86 having a hollow tubular extension 87 projecting through the counterbore 83, the right hand end of the passageway 73, and into the central passageway 71 within the piston rod 2. A gasket ring 88 clamped between the piston rod 2 and a cap 89 secured thereto has sealing and sliding contact with the outer peripheral surface of the tubular extension 87 to prevent leakage of fluid under pressure between the passageways 71 and 73. A plurality of ports 90 in the member 86 connect the interior of the tubular extension 87 to the peripheral surface of member 86 and thence to a passageway 91 extending through the sleeve 76 and opening into the bore 81. A port 92 open at one end to the right hand end of the valve seat member 86 through a valve seat 93 formed thereon is open at the opposite end through a plurality of ports 94 to the peripheral surface of said member, said ports 94 being disposed in a position to register with constantly registering ports 95 and 96 extending respectively, through the sleeve 76 and the piston rod 2 to form a communication between the port 92 and atmosphere. The seat 93 constitutes a seat for a disc type exhaust valve 97 which is adapted to control a fluid pressure communication between passage 85 and atmosphere through ports 92, 94, 95 and 96.

The valve mechanism 75 further comprises a plurality of members assembled in proper relationship in bore 81 by being slipped into the right hand end of said bore and held in place by a plug 98 closing the right hand end of the bore 81 said plug being secured in the sleeve 76 by the cap 77, as will now be described.

In the left hand end of the bore 81 is a gasket ring 99 held in place by a plug 100 having screw-threaded engagement with the sleeve 76, said gasket ring having sealing and sliding contact with the peripheral surface of the exhaust valve seat member 86.

Slipped into the bore 81 with the plug 98 removed, and in the order to be now described, are a plurality of members of the valve mechanism 75 the first of which is a stop 101. The stop 101 comprises a center stop portion 102 adapted to be engaged by the exhaust valve 97 for limiting movement thereof in the direction of the left hand and two spacer elements 103 and 104 having screw-threaded engagement with opposite ends of the center portion 102, the spacer element 103 engaging the plug 100 while

the spacer element 104 engages one side of a partition element 105. The spacer element 103 has adjacent its end opposite the center stop portion 102 a row of circumferentially arranged ports 106 in permanent communication with the ports 95 in sleeve 76. The spacer element 104 has two axially spaced circumferentially arranged rows of ports 106a, one of which rows registers with ports extending through the center stop portion 102 to a chamber 107 surrounding the seat 93 for the exhaust valve 97 while the other row of ports open to a chamber 108 at the opposite side of said valve. The two rows of ports 106a are open to each other through annular clearance space provided between the wall of bore 81 and the outer surface of spacer element 104.

Clamped between the center stop portion 102 and the spacer elements 103 and 104 respectively, are two gasket rings 109 and 110 having sealing and sliding contact with, respectively, the peripheral surface of the exhaust valve seat member 86, and the wall of the bore 81.

The side of the partition element 105 opposite that engaged by the spacer element 104 is engaged by one end of a spacer sleeve 111 having adjacent each end a row of circumferentially arranged ports 112 to provide a fluid pressure communication between portions of a chamber 113 within and encircling said sleeve and which chamber is open to one end of a passageway 114 extending through the sleeve 76 and opening at its opposite end to a chamber 115 formed in the cap 77 at the right hand side of the plug 98. The opposite end of the sleeve 111 engages one side of a second partition element 116, the opposite side of which is engaged by one end of a spacer element 117 constituting a part of a second stop 118 comprising the spacer element 117, a center stop portion 119 for limiting the movement of a second disc type exhaust valve 120 in the direction of the right hand, and a second spacer element 121, said spacer elements 117 and 121 having screw-threaded engagement with opposite ends of the center portion 119. The spacer element 121 has adjacent its end opposite the center stop portion 119 a pair of oppositely arranged elongated slots 122 in permanent registry with a pair of similarly arranged slots 123 in sleeve 76 which latter slots open to atmosphere exteriorly of the piston rod 2. The spacer element 117 has two axially spaced circumferentially arranged rows of ports 124, one of which rows is open through ports extending through the center stop portion 119 to a chamber 125 surrounding a seat 126 formed on a valve seat member 127 which is slidably within a bore 128 extending through the center stop portion 119 and spacer element 121, while the other row of ports opens to a chamber 129 at the opposite side of the valve 120. The two rows of ports 124 are open to each other through annular clearance space provided between the wall of bore 81 and the outer surface of the spacer element 117.

Clamped between the center stop portion 119 and the spacer elements 117 and 121 respectively, are two gasket rings 130 and 131. The gasket ring 130 has sealing and sliding contact with the peripheral surface of the exhaust valve seat member 127, and the gasket ring 131 has sealing contact with the wall of bore 81.

A port 132 open at one end to the left hand end of the valve seat member 127 through the valve seat 126 formed thereon is open at the

opposite end to atmosphere through ports 122 and 123. The seat 126 constitutes a seat for the disc type exhaust valve 120.

The partition elements 105 and 116 are each provided with an axial bore 133 having at the end adjacent the chamber 113 a valve seat 134. Disposed in the chamber 113 are two identical but oppositely arranged valves 135 and 136 for cooperation with the seats 134 on partition elements 105 and 116, respectively. The valves 135 and 136 are provided with fluted stems 137 and 138 respectively, said stems extending through the bores 133 and into engagement with the exhaust valves 97 and 129 respectively. Disposed in the chamber 113 and supported by and bearing against the supply valves 135 and 136 is a spring 139 for urging each of said valves to its seated position.

After all of the elements of the valve mechanism 75 are assembled in the bores 80 and 81 in the order described in the preceding paragraphs, the right hand end of the bore 81 is closed by the plug 98 which engages the right hand end of the spacer element 121. The plug 98 is provided at its right hand side with a shoulder 140 and a threaded portion 141. A gasket ring 142 rests against the shoulder 140 and is locked in place by a lock nut 143 which engages a shoulder 144 formed on the sleeve 76 at the right hand end of the bore 81. The gasket ring 142 engages the wall of bore 81 to prevent leakage of fluid under pressure from the chamber 115 to atmosphere through bores 122 and 123. With the plug 98 and lock nut 143 occupying the above described positions, the cap 77 is screwed into the right hand end of the sleeve 76 until the left hand end thereof engages the lock nut 143 for thereby holding said lock nut and the other parts assembled in the bore 81 in the relation above described. With the valve mechanism 75 thus assembled, the chamber 115 is open through a passageway 145 in the stem 78 of the cap 77 and a flexible hose 146 to a fluid pressure storage reservoir 147 (Fig. 1) which may be charged with fluid under pressure by any suitable means (not shown).

Secured to the right hand end of the exhaust valve seat member 127 are two pins 148 and 149 extending respectively, in opposite directions from said valve seat member through the slots 122 and 123 in the spacer member 121 and sleeve 76 and connected at their outer ends to a spindle member 150 having screw-threaded engagement with the right hand end of the piston rod 2. A lock nut 151 having screw-threaded engagement with the piston rod 2 is provided for engagement with the spindle member 150 to lock said spindle member in an adjusted position with respect to the piston rod 2.

The spindle member 150 is provided with oppositely arranged spindles 152 and 153 connected to the bifurcated end of the rudder operating lever 5.

Slidably extending through a bore 154 in the yoke 10 is a cap screw 155 adjustably connected to the spindle member 150 by screw-threaded engagement for limiting movement of the yoke 10 and the sleeve 76 in the direction of the right hand with respect to the piston rod 2 and the spindle member 150 to a degree just sufficient to effect full opening of the supply valve 135 from its seat 134. A lock nut 157 having screw-threaded engagement with the cap screw 155 is provided for contact with the spindle member 150

to lock said cap screw in an adjusted position with respect to the spindle member 150.

Adjustably connected by screw threads to the yoke 10 is a cap screw 158 having a stem 159 extending into the path of movement of the spindle member 150 for engagement thereby for limiting movement of the yoke 10 and the sleeve 76 in the direction of the left hand with respect to the piston rod 2 and the spindle member 150 to a degree just sufficient to effect full opening of the supply valve 135. A lock nut 160 having screw-threaded engagement with the cap screw 158 is provided for contact with the yoke 10 to lock said cap screw in an adjusted position with respect to the yoke 10.

In order to prevent leakage of fluid under pressure between the chamber 113 and the chambers 108 and 129, the respective partition elements 105 and 116 are each provided with a resilient gasket ring 161 having sealing contact with the wall of the bore 81. In order to prevent leakage of fluid under pressure from the passageway 85 to the passageway 91 and bore 14, two gasket rings 162 are provided, said two rings being carried adjacent the left hand end of the sleeve 76 and having sealing and sliding contact with the plunger 82.

Operation

In operation, let it be assumed that the storage reservoir 147 is charged with fluid to some chosen pressure, such as fifteen hundred pounds per square inch, and that the rudder operating lever 5, the foot operating lever 12, the pistons 18, 19 and 20, the piston rod 2, and the parts of the valve mechanism 75 are occupying the positions in which they are shown in Figs. 1, 2 and 3 of the drawings, for reasons which will become later apparent.

With the storage reservoir 147 charged with fluid under pressure, fluid will flow therefrom to the chamber 115 and thence through the passageway 145 to the chamber 113 wherein it acts on the supply valves 135, 136 to urge them against their seats.

If it is now desired to rock the rudder operating lever 5 (Fig. 1) in a clockwise direction, the pilot will push on the pedal 14 to rock the operating lever 12 in a clockwise direction about the pin 13. The clockwise rocking of the lever 12 about pin 13 will effect, through the cable 11 and the pulley 7, clockwise rocking of the arm 8, which, by reason of its connection to the yoke 10 through the pins 9, will exert a push on said yoke and the sleeve 76 and thereby the partition elements 105 and 116 urging same (Fig. 3) in the direction of the left hand.

The area of the supply valve 135 subjected to pressure of fifteen hundred pounds per square inch present in the chamber 113 is such that as long as the resistance to movement of the power piston 18 and rudder operating lever 5 does not exceed the force pressing said valve against its seat said valve will move in the direction of the left hand simultaneously with the partition element 105. This movement of the supply valve 135 therefore will be transmitted through the fluted stem of said valve, the exhaust valve 97 and the exhaust valve seat member 85 to the piston rod 2 and the power piston 18 which will be moved in the direction of the left hand and actuate the spindle member 150 to correspondingly position the rudder lever 5. While the plane is in flight the pressure of fluid pressing the supply valve 135 to its seat will not permit manual operation of the rudder lever 5 as just described

through more than perhaps one degree from its neutral position at which time the resistance to rudder movement will become so great that by manual pressure on pedal 14 the partition element 105 will be moved away from the supply valve 135 and the exhaust valve 120 will be opened by center stop portion 119 to permit power operation of the rudder, as will be later described. If the pressure of supply fluid in chamber 113 should be less than the intended fifteen hundred pounds, the supply valve 135 will be thus unseated with less manual pressure on the pedal 14 than when said chamber is charged to the full fifteen hundred pounds, as will be apparent.

On the other hand, if the plane is on the ground and the operator is testing movement of the rudder when its resistance to movement is at a minimum, the pressure of fluid in chamber 113 pressing the supply valve 135 to its seat will be sufficient to cause greater manual movement of the rudder lever 5 clockwise than when in flight. Under such a condition it will be noted that with both supply valves 135 and 136 seated, as well as both exhaust valves 97, 120, manual movement of the power piston 18 toward the left hand will act to compress fluid in chamber 23 and reduce pressure of fluid in chamber 24 thereby creating a force, equal to the differential between such pressures acting on the opposite sides of the power piston 18, which opposes the manual pressure on pedal 14. When this force becomes equal to or exceeds the force developed by fluid under pressure in chamber 113 pressing the supply valve 135 to its seat then said valve will become unseated as well as the exhaust valve 120 to permit pressure of fluid in chamber 24 to be increased by flow from chamber 113 past the supply valve 135 and to also permit reducing pressure of fluid in chamber 23 by flow past the exhaust valve 120, whereby the force on piston 18 opposing manual movement thereof by pedal 14 will be so reduced as to permit further turning of the rudder lever 5 by said pedal.

If manual movement of the power piston 18, as just described, is sufficient it will engage the collar 52 of the valve mechanism 34 and force said collar and the stem 46 in the direction of the left hand until the spring 53 is compressed solid after which the false piston 19 will be moved in the direction of the left hand against the force of the spring 31.

At any time when the resistance to clockwise movement of the rudder operating lever 5 requires a force greater than applied manually to pedal 14, the yoke 10 will be moved in the direction of the left hand which will move the sleeve 76 relative to the piston rod 2 and thereby move the exhaust valve 120 away from its seat and at the same time move the partition element 105 away from the supply valve 135. When the supply valve seat 134 is thus moved away from the supply valve 135, fluid under pressure from the reservoir 147, with said reservoir charged, present in the chamber 113 will flow past said valve and along the fluted stem thereof to chamber 108 and then through ports 106a, passageway 85, ports 84, counterbore 83, and passageway 73 in the piston rod 2 to the chamber 24 at the right hand side of piston 18; chamber 23 at the opposite side of said piston being vented at this time past the unseated exhaust valve 120.

As fluid under pressure is thus initially supplied to the chamber 24 it will flow through ports 49 (see Fig. 5) of the valve mechanism 43, the passageway 48 and against the left hand face of the flat disc type supply valve 55. The fluid under

pressure acting on the left hand face of the valve 55 will move said valve against the force of the spring 57 out of contact with the valve seat 45 to permit flow of fluid under pressure through the ports 56 in the valve 55 and thence through the passageway 67 to the chamber 25.

Fluid under pressure will continue to thus flow to the chambers 24 and 25 until the pressure in chamber 24 acting on the right hand face of the main power piston 18 is great enough to overcome the resistance to movement of the rudder lever 5 at which time the piston 18 and piston rod 2 will be moved in the direction of the left hand to thereby rock the rudder lever 5 in a clockwise direction about the rudder post 6.

Movement of the piston rod 2 in the direction of the left hand carries with it the exhaust valve seat members 86 and 127. As the member 86 moves in the direction of the left hand, the force of spring 139 acting on the supply valve 135 will, through the fluted stem of said valve, maintain the exhaust valve 97 in contact with the valve seat 98 and move the supply valve 135 in the direction of the left hand. Assuming that less than full movement of pedal 14, sleeve 76 and partition 105 is effected, the supply valve 135 will thus continue to move until it seats on the seat 134 which terminates further flow of fluid under pressure from the storage reservoir 147 to the chambers 24 and 25, whereupon movement of the piston 18, piston rod 2 and rudder operating lever 5 will cease with the rudder operating lever 5 in a position corresponding to the position of the pedal 14, it being noted that the exhaust valve 120 will also reseat at the same time as the supply valve 135.

If the pilot pushes on the pedal 14 to cause a further clockwise rocking of the operating lever 12 about the pin 13, the arm 8 will be further rocked clockwise to move the sleeve 76 further in the direction of the left hand to again open the supply valve 135 to supply fluid under pressure from the storage reservoir 147 to the chambers 24 and 25 and to at the same time open the exhaust valve 120 to vent chamber 23. Fluid under pressure will thus flow from the storage reservoir 147 to the chambers 24 and 25 until the pressure in the chamber 24 is great enough to overcome the resistance to movement of the rudder lever 5 and move the piston 18 and piston rod 2 further in the direction of the left hand to a new position corresponding to that of pedal 14 and in which the supply valve 135 and exhaust valve 120 are again closed in the manner hereinbefore described.

It is therefore seen that the pilot, by pushing on the pedal 14, may supply fluid under pressure to the chambers 24 and 25 until the chamber 24 is charged to any degree of pressure necessary to effect positioning of the rudder lever 5 to correspond to that of said pedal.

If the pilot desires to move the rudder lever 5 in a counterclockwise direction, he will push on the pedal 15 to rock the operating lever 12 in a counterclockwise direction about the pin 13. The counterclockwise rocking of the lever 12 about pin 13 will effect, through the cable 11 and the pulley 7, counterclockwise rocking of the arm 8 which, by reason of its connection to the yoke 10 through the pins 9, will pull said yoke and the sleeve 76 in the direction of the right hand.

If the force required to turn the rudder lever 5 counterclockwise does not exceed that applied to the pedal 15 then counterclockwise rotation 75 will occur solely by manual pressure on pedal

15 the same as clockwise rotation resulted from manual pressure on pedal 14, as above described, but if the resistance to counterclockwise movement of the rudder lever 5 requires a greater force, the manual movement of sleeve 76 in the direction of the right hand will be relative to piston rod 2 and will move the seat 134 away from the supply valve 136 whereupon fluid under pressure present in the chamber 113 will flow past said valve, along the fluted stem of said valve, through ports 124, passageway 91, ports 90 in the tubular extension 87 and central passageways 71 and 72 to the chamber 23.

As the sleeve 76 moves in the direction of the right hand relative to piston rod 2 it carries with it the stop 101; as hereinbefore mentioned, and thereby lifts the exhaust valve 97 from its seat 93 on the right hand end of the exhaust valve seat member 86. As the exhaust valve 97 is moved away from the seat 93 the chamber 24 is opened to atmosphere through the passageway 73, counterbore 83, ports 34, the passageway 85, ports 108a past the open exhaust valve 97 and through the ports 92, 94 in the exhaust valve seat member 86, port 106 in the spacer element 103, and ports 95 and 96 in sleeve 76 and piston rod 2 respectively thus venting fluid under pressure from the chamber 24 at the same time that fluid under pressure is being supplied to the chamber 23.

It is desired to point out that fluid under pressure is vented only from the chamber 24 since the spring 57 will maintain the valve 55 seated and prevent back flow of fluid under pressure from the chamber 25 to chamber 24.

The fluid under pressure supplied to the chamber 23 flows through the ports 49 (see Fig. 5) of the valve mechanism 34, passageway 48 and against the right hand face of the valve 55. The fluid under pressure acting on the right hand face of the valve 55 moves said valve against the force of the spring 57 out of contact with the valve seat 45 to permit flow through the ports 56 in said valve and thence through the passageway 67 to the chamber 22.

Fluid under pressure will thus continue to flow to the chambers 22 and 23 and from the chamber 24 in the manner described in the foregoing paragraphs until the differential in pressures acting across the main piston 18 is great enough to overcome the resistance to movement of the rudder operating lever 5 at which time the piston 18 and piston rod 2 will be moved in the direction of the right hand to thereby rock the rudder lever 5 in a counterclockwise direction about the rudder post 6.

Movement of the piston rod 2 in the direction of the right hand carries with it through the pins 148 and 149 the exhaust valve seat member 127. As the member 127 moves in the direction of the right hand, the force of the spring 139 acting on the supply valve 136 will, through the fluted stem of said valve, maintain the exhaust valve 126 in contact with the valve seat 126 and move the supply valve 136 in the direction of the right hand. Assuming that less than full movement of pedal 15, sleeve 76 and partition 116 is effected, the supply valve 136 will thus continue to move until it seats on the seat 134 in a position of piston 18 corresponding to that of the pedal 12 and which terminates further flow of fluid under pressure from the storage reservoir 147 to the chambers 22 and 23 whereupon movement of the piston 18, piston rod 2 and rudder operating lever 5 will cease with the rudder

operating lever 5 in a position corresponding to the position of pedal 15.

Movement of the piston rod 2 in the direction of the right hand also carries with it the exhaust valve seat member 86 which will engage the exhaust valve 97 at substantially the same time that the supply valve 136 engages its seat 134 thus simultaneously terminating exhaust of fluid under pressure from the chamber 24 and the supply of fluid under pressure to the chambers 22 and 23.

If the pilot pushes on the pedal 15 to cause further counterclockwise rocking of the operating lever 12 about the pin 13, the arm 8 will be further rocked counterclockwise to move the sleeve 76 in the direction of the right hand to again open the supply valve 136 to supply fluid under pressure from the storage reservoir 147 to the chambers 22 and 23, and the exhaust valve 97 will be opened to release fluid under pressure from the chamber 24, and such supply and release will continue until the pressure differential across the main power piston 18 is great enough to overcome the resistance to movement of the rudder lever 5 and move the piston 18 and the piston rod 2 in the direction of the right hand until the valves 136 and 97 are closed in the manner hereinbefore described.

It is therefore seen from the foregoing description that the pilot, by pushing on the pedal 15, may supply fluid under pressure to chambers 22 and 23 until the chamber 23 is charged to the degree of pressure necessary to effect desired positioning of the rudder operating lever 5.

In order to return the rudder lever 5 to any desired position in a clockwise direction of movement, the pilot will push on pedal 14 to thereby actuate the sleeve 76 to open the supply valve 135 and exhaust valve 120 whereupon fluid under pressure will be supplied to chamber 24 and at the same time released from chamber 23 until a sufficient differential in pressure is established on opposite sides of piston 18 to move the rudder lever 5 clockwise to the position corresponding to that of said pedal.

It will now be seen that by operation of pedals 14 or 15 any desired position of the rudder lever 5 will be effected by pressure of fluid acting on the power piston 18 when the resistance to movement of said lever is in excess of that required to permit manual movement of said lever as hereinbefore described.

In the power operation above described, that is, movement of piston 18 between positions in which it will just contact collars 52 on the valve mechanisms 34 and 43, respectively, the chambers 22 and 25 at the outer faces of the false pistons 19 and 20 will be only once charged with fluid under pressure by flow of fluid under pressure from chambers 23, 24, respectively, as upon the initial operation of pedals 14 and 15, after which they will remain charged due to the closed check valves 55 during operation of the piston 18 between said positions, whereby with the false pistons 16, 17 in their innermost positions pressure changes need be effected only in the relatively small chambers at opposite sides of piston 18 to effect positioning of the rudder lever 5, thereby conserving fluid under pressure and obtaining quicker response of said piston to operation of the pedals 14 and 15 than if chambers 22 and 25 were a part of and constantly open to chambers 23 and 24, respectively, as in conventional motors.

The power operation above described is, it will

be noted, limited to movement of the power piston 18 to positions between the false pistons 19, 20 when in their inner positions, in which they are shown in the drawing, such movement of said power piston being adequate to provide such adjustment of a rudder as will usually be required during normal flight of a plane.

Now assume that the operator desires to move the rudder lever 5 from a neutral position, in which said lever and piston 18 are shown in the drawing, in a clockwise direction to an extent greater than for normal flight and requiring greater movement of piston 18 than just into contact with collar 52 of the valve mechanism 34. To thus position the rudder lever 5, the pilot will push pedal 14 to the position desired for lever 5 and thereby open the supply valve 135 to cause fluid under pressure to be supplied to the chambers 24 and 25 and at the same time open the exhaust valve 120 for venting fluid under pressure from the chamber 23 in the manner hereinbefore described. The piston 18 will then move in the direction of the left hand until the left hand face of said piston engages the collar 52 of the valve mechanism 34. Upon the left hand face of the piston 18 engaging the collar 52 of the valve mechanism 34, continued movement of the piston 18 in the direction of the left hand will displace the stem 46 and valve 55 of said valve mechanism in the direction of the left hand until the spring 53 is compressed solid which not only opens the valve 55 but also through the fluted stem 68 lifts the exhaust valve 64 from its seat 61 against the force of spring 69. Fluid under pressure will thereby be vented from chamber 22 through the passageway 67, bore 62, past the unseated exhaust valve 64, chamber 68, and passageways 33 and 32 to atmosphere whereby the false piston 19 will move with piston 18, resisted only by spring 31, until piston 18 obtains the position corresponding to that of pedal 14. Upon the pilot ceasing to press on the pedal 14, the piston 18, piston rod 2, exhaust valve seat member 38, and exhaust valve 97 will continue to move in the direction of the left hand until spring 139 seats supply valve 135 to cut off the supply of fluid under pressure to the chamber 24 and the exhaust valve 120 seats to prevent further release of fluid under pressure from chamber 23 whereupon the pistons 18 and 19 and rudder operating lever 5 will come to rest in a position in which said piston occupies a position at the left of the position in which the false piston 19 is shown in Fig. 2 and the rudder operating lever 5 will occupy an angular position to the left of the position shown in Fig. 1 of the drawings. With the piston 18 at rest, fluid under pressure in chamber 22 will continue to flow to atmosphere past the open valve 64 in valve device 34 and through passageways 33 and 32 until the pressure in chamber 22 is reduced below that in chamber 23 sufficiently to permit the pressure in chamber 23 to move the piston 19 further in the direction of the left hand until the spring 69 seats exhaust valve 64 and the pressure retained in chamber 22 together with the force of spring 31 balances the pressure in chamber 23.

Now let it be assumed that with the pistons 18 and 19 and the rudder operating lever 5 occupying the positions just described, the pilot desires to rock said lever in a counterclockwise direction about rudder post 6. To rock the rudder operating lever 5 counterclockwise, the pilot

will push on the pedal 15 which will cause fluid under pressure to be supplied to the chamber 23 and vented from the chamber 24 in the manner hereinbefore explained.

Fluid under pressure thus supplied to chamber 23 will flow through ports 49 and passageway 48 in stem 46 of valve mechanism 34 and against the right hand face of the supply valve 55 over an area equal to the area of the passageway 48. When the pressure in chamber 23 and passageway 48 is thus raised sufficiently to overcome the force of spring 57 on the supply valve 55 said valve will move out of engagement with collar 45 whereupon fluid under pressure will again flow to chamber 22 to charge same to substantially the pressure in chamber 23. When the increase in pressure in chamber 23 and the decrease in pressure in chamber 24 has continued sufficiently to establish a differential in pressures on the opposite sides of piston 18 sufficient to overcome the resistance to movement of the rudder operating lever 5, the piston 18 will move in the direction of the right hand to rock the rudder lever 5 counterclockwise.

As the main piston 18 thus moves in the direction of the right hand, the spring 31 will move the false piston 19 in the same direction, the false piston 19 following the main piston 18 until the collar 28 engages the stop member 29 which will prevent further movement of the false piston 19, but during such movement fluid under pressure will continue to flow to chamber 22 past the valve 55 to maintain such pressure equal substantially to that in chamber 23.

The distance the piston 18 is moved in the direction of the right hand will of course depend on the displacement of the pedal 15 by the pilot, the rudder operating lever 5 being always moved to a position corresponding to the position of the pedal 15. If the pilot desired that piston 18 be moved further in the direction to the right than just into engagement with collar 52 of valve mechanism 43, then by continuing to move pedal 15 the piston 18 will correspondingly move and during such movement operate the valve mechanism 43 to vent fluid under pressure from the chamber 25 so that the false piston 20 will move in the same direction, until piston 18 obtains the position corresponding to that of pedal 15. The operation of the valve mechanism 43 to vent the chamber 25 is identical with the operation of the valve mechanism 34 to vent the chamber 22 as hereinbefore described.

Upon the pilot discontinuing to push on the pedal 15, the valve mechanism 75 will operate in the manner hereinbefore described to cut off the supply of fluid under pressure to the chambers 22 and 23 and the venting of fluid under pressure from the chamber 24. Thus, by pushing the pedal 15 to any selected position, the pilot may effect movement of the piston 18 to any corresponding position between the position which piston 18 would occupy when the false piston 19 is moved to its final position in the direction of the left hand and the position which piston 18 would occupy when the false piston 20 is moved to its final position in the direction of the right hand.

If prior to charging the storage reservoir 147 and chamber 113 with fluid under pressure, the operator desires to test, on the ground, turning of the rudder lever 5 clockwise from neutral position and pushes on pedal 14 to accomplish same, under which condition the supply valve 135 will be pressed to its seat only by the slight force of

bias spring 139, the spacer elements 121 and 103 and partition elements 116 and 105 will move with the yoke 10 relative to the exhaust valve seat members 127 and 86 permitting the spacer element 121 to open the exhaust valve 120 and the seat member 86 to open the supply valve 135. With the exhaust valve 120 open chamber 23 will be open to atmosphere while with the supply valve 135 open chamber 24 will be opened to chamber 113 and thereby to the fluid pressure storage reservoir 147 at atmospheric pressure. Continued pressing against pedal 14 will thus cause the piston 18 to be moved, with substantial equal fluid pressures acting on opposite sides, to move the rudder lever 5 and correspondingly position the plane's rudder, the exhaust valve 120 and supply valve 135 remaining open during such continued operation. In contrast to the illustration, the volume of the supply reservoir 147 will be relatively great as compared to the volume of chamber 24 so that the reduction in pressure in said chamber resulting from movement of piston 18 toward the left hand will be substantially negligible with respect to manual effort applied to pedal 14.

If movement of the pedal 14 is such as to cause piston 18 to engage collar 52 of valve mechanism 34 and open the respective exhaust valve 64, chamber 22 will remain at atmospheric pressure during further movement of said piston whereby only the light pressure of spring 31 will oppose further movement of pedal 14.

On the other hand, if the pedal 15 is operated to turn the rudder lever 5 counterclockwise, the exhaust valve 87 and supply valve 136 will be opened, and finally valve 64 in the valve mechanism 43 if pedal movement is sufficient, to permit manual movement of piston 18 the same as just described in connection with manual turning of rudder lever 5 in a clockwise direction.

Summary

It will now be seen that by the use of the false pistons 19 and 20 in a relatively long stroke motor the amount of fluid under pressure required for effecting chosen shorter stroking of the motor is less than in conventional motors since after the initial operation of the motor the necessary pressure variations need only be effected in the relative small chambers 23 and 24, but when longer stroking of the motor is desired the pistons 19 and 20 will be displaced as necessary.

Having now described the invention, what I claim as new and desire to secure by Letters Patent, is:

1. A fluid motor comprising a casing having a bore, a double acting power piston slidably mounted in said bore, two false pistons slidably mounted in said bore, one at either side of said power piston, and cooperative with said power piston to form two main pressure chambers one at either side of said power piston, an auxiliary pressure chamber at the opposite side of each false piston, means acting on each false piston urging it toward said power piston to a position providing for limited movement of said power piston between the two false pistons, means for conveying fluid under pressure to the main pressure chamber at either side of said power piston and for at the same time venting the main pressure chamber at the opposite side, one way flow means for conveying fluid under pressure to each auxiliary chamber upon supply of fluid under pressure to the adjacent main pressure

chamber, and means operative by said power piston upon movement into substantial contact with either of said false pistons to release fluid under pressure from the auxiliary pressure chamber at the opposite side of the respective false piston.

2. A fluid motor comprising a casing having a bore, a double acting power piston slidably mounted in said bore, two false pistons slidably mounted in said bore, one at either side of said power piston, and cooperative with said power piston to form two main pressure chambers one at either side of said power piston, an auxiliary pressure chamber at the opposite side of each false piston, means acting on each false piston urging it toward said power piston to a position providing for limited movement of said power piston between the two false pistons, means for conveying fluid under pressure to the main pressure chamber at either side of said power piston and for at the same time venting the main pressure chamber at the opposite side, and valve means carried by each of said false pistons comprising a check valve in a communication providing for flow of fluid under pressure only from the main pressure chamber at one side of the respective false piston to the auxiliary pressure chamber at the opposite side, and a release valve for venting fluid under pressure from the respective auxiliary pressure chamber operative by said power piston upon substantial contact with the respective false piston.

3. A fluid motor comprising a casing having a bore, a double acting power piston slidably mounted in said bore, two false pistons slidably mounted in said bore, one at either side of said power piston, and cooperative with said power piston to form two main pressure chambers one at either side of said power piston, an auxiliary pressure chamber at the opposite side of each false piston, means acting on each false piston urging it toward said power piston to a position providing for limited movement of said power piston between the two false pistons, means for conveying fluid under pressure to the main pressure chamber at either side of said power piston and for at the same time venting the main pressure chamber at the opposite side, one-way flow means operative upon supply of fluid under pressure to either one of said main pressure chambers to charge the auxiliary pressure chamber at the opposite side of the respective false piston with fluid at substantially the same pressure, and means operative by said power piston upon substantial contact with either false piston to release fluid under pressure from the auxiliary chamber at the opposite side of the respective false piston.

4. A fluid motor comprising a casing having a bore, a double acting power piston slidably mounted in said bore, two false pistons slidably mounted in said bore, one at either side of said power piston, and cooperative with said power piston to form two main pressure chambers one at either side of said power piston, an auxiliary pressure chamber at the opposite side of each false piston, means acting on each false piston urging it toward said power piston to a position providing for limited movement of said power piston between the two false pistons, means for conveying fluid under pressure to the main pressure chamber at either side of said power piston and for at the same time venting the main pressure chamber at the opposite side, a communication through each false piston providing for flow

of fluid under pressure from the main pressure chamber at one side of the respective false piston to the auxiliary pressure chamber at the opposite side, a check valve in said communication for preventing reverse flow of fluid under pressure therethrough, another communication in each false piston for releasing fluid under pressure from the respective auxiliary pressure chamber, a release valve for closing the last named communication, and means operative by said power piston upon substantial contact with either false piston to open the respective release valve.

5. A fluid motor comprising a casing having a bore, a double acting power piston slidably mounted in said bore, two false pistons slidably mounted in said bore, one at either side of said power piston, and cooperative with said power piston to form two main pressure chambers one at either side of said power piston, an auxiliary pressure chamber at the opposite side of each false piston, means acting on each false piston urging it toward said power piston to a position providing for limited movement of said power piston between the two false pistons, means for conveying fluid under pressure to the main pressure chamber at either side of said power piston and for at the same time venting the main pressure chamber at the opposite side, a communication through each false piston providing for flow of fluid under pressure from the main pressure chamber at one side of the respective false piston to the auxiliary pressure chamber at the opposite side, a check valve in said communication for preventing reverse flow of fluid under pressure therethrough another communication in each false piston for opening the respective auxiliary chamber to atmosphere, a release valve in each false piston normally closing the last named communication, and means operative by said power piston upon substantial contact with either false piston to open the respective release valve.

6. A fluid motor comprising a casing having a bore, a double acting power piston slidably mounted in said bore, two false pistons slidably mounted in said bore, one at either side of said power piston, and cooperative with said power piston to provide two main pressure chambers, one at either side of said power piston, a rod projecting from said power piston having two axially extending passageways, one open to each of said pressure chambers, through which fluid under pressure is adapted to be supplied to either of said chambers and at the same time released from the other chamber, an auxiliary pressure chamber at the opposite side of each false piston, a rod associated with each false piston, a stop associated with the rod of each false piston arranged to cooperate with said casing to limit movement of the false pistons in the direction of said power piston, a spring acting on each false piston urging it in the direction of said power piston, one-way flow means providing for charging each auxiliary chamber with fluid at substantially the pressure provided in the main pressure chamber at the opposite side of the respective false piston, a communication in each false piston and the respective rod for opening the respective auxiliary chamber to atmosphere, and a valve normally closing the last named communication and operative by said main piston upon substantial contact with the respective false piston to open the last named communication.

7. A fluid motor comprising a casing having

a bore, a double acting power piston slidably mounted in said bore, two false pistons slidably mounted in said bore, one at either side of said power piston, and cooperative with said power piston to provide two main pressure chambers, one at either side of said power piston, a rod projecting from said power piston having two axially extending passageways, one open to each of said pressure chambers, valve means carried by said rod operative to supply fluid under pressure to either of said passageways while at the same time venting fluid under pressure from the other passageway, an auxiliary pressure chamber at the opposite side of each false piston, a rod associated with each false piston, a stop associated with the rod of each false piston arranged to cooperate with said casing to limit movement of the false piston in the direction of said power piston, a spring acting on each false piston urging it in the direction of said power piston, one-way flow means providing for charging each auxiliary chamber with fluid at substantially the pressure provided in the main pressure chamber at the opposite side of the respective false piston, a communication in each false piston and the respective rod for opening the respective auxiliary chamber to atmosphere, and a valve normally closing the last named communication and operative by said main piston upon substantial contact with the respective false piston to open the last named communication.

8. A fluid motor comprising a casing having a bore, a double acting power piston slidably mounted in said bore, two false pistons slidably mounted in said bore, one at either side of said power piston, and cooperative with said power piston to provide two main pressure chambers, one at either side of said power piston, a rod projecting from said power piston having two axially extending passageways, one open to each of said pressure chambers, valve means carried by said rod for controlling supply and release of fluid under pressure to and from said passageways, means operative manually relative to said rod to actuate said valve means to selectively supply fluid under pressure to either one of said passageways and at the same time to release fluid under pressure from the other passageway, means operative by said rod in response to movement thereof relative to said manually operative means to actuate said valve means to bottle up fluid under pressure in each of said passageways, an auxiliary pressure chamber at the opposite side of each false piston, a rod associated with each false piston, a stop associated with the rod of each false piston arranged to cooperate with said casing to limit movement of the false piston in the direction of said power piston, a spring acting on each false piston urging it in the direction of said power piston, one-way flow means providing for charging each auxiliary chamber with fluid at substantially the pressure provided in the main pressure chamber at the opposite side of the respective false piston, a communication in each false piston and the respective rod for opening the respective auxiliary chamber to atmosphere, and a valve normally closing the last named communication and operative by said main piston upon substantial contact with the respective false piston to open the last named communication.

9. In combination, a pivoted rockable lever, manual means for rocking said lever, and a booster power cylinder operable also to rock said lever upon the resistance to movement of said

lever exceeding a chosen valve, said power cylinder comprising a casing having a bore, two pistons disposed in said bore, means for limiting the movement of each of said pistons in the direction of the other, a third piston slidably disposed in said bore between said two pistons, a piston rod secured at one end to said third piston and at the other end exteriorly of said casing to said rockable lever, a counterbore in said other end of said piston rod, a sleeve slidably disposed in said counterbore and having an operative connection with said manual means, a first self-lapping valve means carried in said sleeve and operative by said manual means upon the resistance to rocking of said lever in one direction exceeding said chosen value to supply fluid under pressure to one face and to release fluid under pressure from the opposite face of said third piston, a second self-lapping valve means carried in said sleeve and operative by said manual means upon the resistance to rocking of said lever in the opposite direction exceeding said chosen value to supply fluid under pressure to said opposite face and to release fluid under pressure from said one face of said third piston, means including a check valve carried by each of said two pistons operable to establish a one-way flow fluid pressure communication through each of said two pistons upon supply of fluid under pressure to that face of said third piston adjacent the respective one of said two pistons and to close said communication upon the release of fluid under pressure from that face of said third piston adjacent the respective one of said two pistons, and means operative upon said third piston substantially engaging either one of said two pistons to release fluid under pressure from the opposite side of the last named piston to permit movement then of said third piston.

10. In combination, a pivoted rockable lever, a manual means for rocking said lever, a source of fluid under pressure, and a power cylinder comprising a first piston having an operative connection with said lever, a first self-lapping valve means operative by said manual means, upon the resistance to rocking of said lever in one direction exceeding a chosen value, to supply fluid under pressure from said source to one face of said first piston to cause rocking of said lever in one direction in response to movement of said first piston, a second self-lapping valve means operative by said manual means, upon the resistance to rocking of said lever in the opposite direction exceeding said chosen value, to supply fluid under pressure from said source to the opposite face of said first piston to cause rocking of said lever in the opposite direction in response to movement of said first piston, a second and a third piston disposed respectively on opposite sides of said first

piston to form two pressure chambers on each side of said first piston, means for limiting movement of said second and third pistons in the direction of each other to provide a chosen length of stroke of said first piston without engaging either of said two pistons, valve means carried by each of said second and third pistons to effect charging the respective chambers on that side of said second and third pistons opposite said first piston with fluid at substantially the maximum pressure effective on the adjacent face of said first piston, and exhaust valve means carried by each of said second and third pistons and operable by said first piston upon the stroke of said first piston in one or the other direction exceeding said chosen length to release fluid under pressure from the respective chamber on that side of the respective second or third piston opposite said first piston.

11. In combination, a rockable lever, a fluid motor comprising a casing having a bore, a first piston slidably disposed in said bore and having a driving connection with said lever, two pistons disposed in said bore one on each side of said first piston and each cooperating with said first piston to form a first pressure chamber at each side of said first piston, said two pistons cooperating with said casing to form a second pressure chamber at the opposite side of each of said two pistons, a first valve means operative to simultaneously supply fluid under pressure to one of said first chambers and to release fluid under pressure from the other of said first chambers to move said first piston to rock said lever, one-way flow valve means carried by each of said two pistons and effective to cause charging of the second chamber at one side of the respective one of said two pistons upon supply of fluid under pressure to the opposite side, and exhaust valve means carried by each of said two pistons and operative by said first piston upon substantial engagement of said first piston with the respective one of said two pistons to release fluid under pressure from said second chamber at the opposite side of the last named piston.
